UNITED STATES PATENT OFFICE

2,469,714

SPILL PORT CONTROL FOR FREE-PISTON UNITS

Kenneth C. Cooper, Portland, Conn., assignor to
United Aircraft Corporation, East Hartford,
Conn., a corporation of Delaware

Application August 23, 1944, Serial No. 550,877

8 Claims. (Cl. 230—56)

1

This invention relates to a control for the spill ports of a free-piston engine-and-compressor unit.

The copending application of Cooper, Serial No. 531,301, filed April 15, 1944, now Patent No. 2,458,147, discloses a free-piston unit in which the effective volume of the compressor is adjusted by opening or closing a number of axially spaced spill ports in the compressor cylinder. A feature of this invention is a device for opening and closing the ports.

A circumferentially movable band for closing the spill ports is claimed in the copending Kalitinsky application, Serial No. 550,884, filed August 23, 1944, now Patent No. 2,441,272, in which the spaced ends of the band are held together by a spring to keep the band tight on the cylinder. A feature of this invention is a self-sealing band which does not require a spring to maintain the band in port-sealing position.

Another feature is a sealing band which surrounds the cylinder and is guided by an overlying stationary ring which has ports in line with the ports in the compressor cylinder.

A feature of the invention is a lightweight structure for controlling the spill ports which will require little power for adjusting it and which will occupy a small space.

Other objects and advantages will be apparent from the specification and claims, and from the accompanying drawings which illustrate an embodiment of the invention.

Fig. 1 is a sectional view through the free-piston unit.

Fig. 2 is a sectional view on line 2—2 of Fig. 1.

Fig. 3 is a fragmentary view on line 3—3 of Fig. 2.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from the center of the engine cylinders by a linkage, not shown.

Intake manifold 42, which extends around the compressor and engine cylinders conducts air to

2

intake valves 44 in the heads of the compressor cylinders, through which air alternately enters opposite ends of the cylinders. The compressed air leaves the cylinders through discharge valves 46, also at opposite ends of the compressor cylinders and passes into a central scavenging chamber 48 and end chambers 50 and 52. These chambers may be interconnected by a scavenging manifold, not shown.

Compressed air from the scavenging chambers enters engine ports 54 and 56 which are uncovered by piston 12 and 14 at the end of the power stroke, thereby permitting air to be blown through the engine cylinder. Gas and air in the engine cylinders is discharged through exhaust ports 58 into exhaust manifold 60.

Each compressor cylinder has one or more axially spaced rows of spill ports 62 to permit discharge of air without compression from the cylinder. Each row of ports may be individually controlled by a band 64, Fig. 3, extending around the cylinder between projecting ribs 66 extending from the cylinder, and having spaced openings 68, Fig. 2, for alignment with the spill ports.

Band 64 is relatively thin and is supported by a ring 70 extending around the cylinder outside of the band and having spaced openings 72 which are in line with the spill ports. Ring 70 may be held in position between the adjacent projecting ribs 66 by clamping wires 74 fitting in grooves 76 in the projecting ribs. Each ring 70 is enough larger than band 64 so that the band is free to move between the outer periphery of the compressor cylinder and the surrounding ring.

Band 64 may have projecting lugs 78 on opposite ends fitting in notches 80 in a gear block 82 located between opposite ends of the overlying ring. The gear block permits the band to be moved circumferentially for aligning the openings in the band with the ports in the cylinder. As shown, the block has a rack 84 engaging with a pinion 86 on a shaft 88 parallel to the axis of the compressor cylinder. Rotation of pinion 86 will adjust band 64. The structure by which the pinion is moved, not being part of this invention, will not be described in detail.

The lugs 78 fit freely in gear block 82 to permit the band 64 to move into engagement with the cylinder wall when the pressure in the cylinder is less than the external pressure. If the pressure in the cylinder is higher than the surrounding pressure, the band may move against the surrounding ring when the band is in ports closing position. In either case the band seals the ports against leakage without the necessity for a ten-

sioning spring to hold the band on the cylinder.

It is to be understood that the invention is not limited to the specific embodiment herein illustrated and described, but may be used in other ways without departure from its spirit as defined by the following claims.

I claim:

1. A free-piston engine-and-compressor unit including a compressor piston and cylinder, said cylinder having at least one circumferential row of spill ports therein, a band extending circumferentially around said cylinder and being movable on said cylinder into a position to cover the ports, and a ring extending around the cylinder and overlying the band to form a channel in which the band may move, said ring having ports aligned with the ports in the cylinder, and said band having ports movable into and out of alignment with the ports in the cylinder and ring.

2. A free-piston engine-and-compressor unit including a compressor piston and cylinder, said cylinder having at least one circumferential row of spill ports therein, a band extending circumferentially around said cylinder and being movable on said cylinder into a position to cover the ports, and a ring extending around the cylinder and overlying the band, said ring having spaced ports aligned with the cylinder ports, said band having spaced openings therein corresponding to the spacing of the spill ports and being movable circumferentially between said cylinder and ring for opening or closing the spill ports.

3. A free-piston engine-and-compressor unit including a compressor piston and cylinder, said cylinder having at least one circumferential row of spill ports therein, a band extending circumferentially around said cylinder to cover the ports, said cylinder having guide means thereon on opposite sides of the row of ports for guiding the band for circumferential movement, and a ring extending around the cylinder and overlying the band, said ring being connected to said guide means and having ports aligned with the ports in the cylinder, and said band having spaced ports adapted for alignment with the cylinder and ring ports by movement of the band circumferentially between the ring and cylinder.

4. A free-piston engine-and-compressor unit including a compressor piston and cylinder, said cylinder having at least one row of spill ports therein, means on the cylinder for forming with said cylinder a circumferentially extending guide channel overlying said row of ports, and a band movable circumferentially in said channel for opening and closing said ports, said band having openings therein which are moved into and out of alignment with the ports, said means having ports aligned with the cylinder ports.

5. A free-piston engine-and-compressor unit including a compressor piston and cylinder, said cylinder having at least one circumferential row of spill ports therein, a band extending circumferentially around and movable on said cylinder to cover the ports and a ring extending around the cylinder and overlying the band, said ring having openings therein aligning with the spill ports in the cylinder and said band having openings movable into and out of alignment with the ports in the cylinder and with the openings in the ring by movement of the band on the cylinder.

6. A free-piston engine-and-compressor unit

including a compressor piston and cylinder, said cylinder having at least one circumferential row of spill ports therein, a band extending circumferentially around said cylinder and being movable on said cylinder into a position to cover the ports, and a ring extending around the cylinder and overlying the band to form a channel in which the band may move, said band having spaced ports corresponding in spacing with the cylinder ports for alignment with the cylinder ports, said band being movable on the surface of the cylinder for aligning the ports, said ring being constructed and arranged to provide for flow of fluid into and out of said cylinder when said ports in the band and cylinder are in alignment.

7. A free-piston engine-and-compressor unit including a compressor piston and cylinder, said cylinder having at least one circumferentially extending row of spill ports therein, a band extending circumferentially around the cylinder and being movable on the cylinder to close the ports, said band having ports movable into and out of alignment with the cylinder ports, guide means on the cylinder on opposite sides of the ports for guiding the band and a guide overlying the band and spaced from the cylinder to permit movement of the band between said guide and cylinder, said guide having ports aligned with the cylinder ports and being supported in position by said guide means.

8. A free-piston engine-and-compressor unit including a compressor piston and cylinder, said cylinder having at least one circumferentially extending row of spill ports therein, a band extending around said cylinder to cover the ports, guide means on the cylinder on opposite sides of the ports for guiding the band and a ring extending around the cylinder and overlying the band, said ring having ports aligned with the cylinder ports and being supported in overlying relation to the band by said guide means, said band having openings therein which are moved into and out of alignment with the ports, said band having a projecting lug by means of which the band is moved, the ends of the ring being spaced to accommodate the lugs.
